UNITED STATES PATENT OFFICE.

WILLIAM M. McCLEAREN, OF DINUBA, CALIFORNIA.

FASTENING DEVICE.

1,269,626.

Specification of Letters Patent. Patented June 18, 1918.

Application filed June 16, 1917. Serial No. 175,095.

To all whom it may concern:

Be it known that I, WILLIAM M. McCLEAREN, a citizen of the United States, residing at Dinuba, in the county of Tulare and State of California, have invented a new and useful Fastening Device, of which the following is a specification.

The device forming the subject matter of this application is a fastening means for articles of wearing apparel, such as shoes, although the invention is not confined in its use to articles of footwear.

The invention aims to provide novel means whereby through the reciprocation of a rider, the edges of separable parts may be brought together, to cause fasteners carried by said edges to interlock with each other.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings:—

Fig. 1 shows in perspective, an article of footwear wherein the device forming the subject matter of this application has been embodied;

Fig. 2 is a detail in the nature of a front elevation enlarged from Fig. 1, parts being broken away;

Fig. 3 is a cross section taken approximately on the line 3—3 of Fig. 2;

Fig. 4 is a fragmental longitudinal section showing the rider and parts which co-operate therewith;

Fig. 5 is a side elevation of the rider;

Fig. 6 is a fragmental elevation showing a modified form of the invention;

Fig. 7 is a fragmental cross section showing a slight modification in the invention;

Fig. 8 is a cross section showing a further modification in the invention;

Fig. 9 is an elevation showing a modified application of the invention; and

Fig. 10 is a section taken approximately on the line 10—10 of Fig. 9.

In Fig. 1 of the drawings there is shown an article of wearing apparel such as a shoe, including an upper 1 having sides 2 and 3. 60 A front piece 4 is secured adjustably to the side 3 in any desired manner. In the present instance, but not of necessity, the front piece 4 is stitched to the part 3, as shown at 5. If desired, the front piece 4 may be 65 omitted entirely, as will be obvious when the nature of the invention is better understood.

Folded strips 6 of flexible material are provided, and the free edges of these strips 70 6 extend beneath the side 2 and the front piece 4, if the latter is used. The strips 6 are attached to the parts 3 and 2 by fasteners 7 of any desired sort. In the present instance, the fasteners 7 take the form of 75 headed pins having bendable prongs passing through the strips 6 and engaging the same. At their inner edges, the strips form enlarged loops 8 within which are located and held flexible elements 9 which may be cords. 80 The flexible elements 9 extend upwardly above the top edge of the upper 1 and terminate in finger pieces 10. Fasteners 11 of U-shape and preferably made of metal are clamped onto the looped portion 8 of one 85 strip 6, and because this loop is enlarged by the cord 9, the fasteners 11 cannot slide transversely off the strip 6. Each fastener 11 is slit at its lower end to form a depending offset tongue 12. With the other strip 90 6 is assembled a fastener 14 which may be made of metal. The fastener 14 at its upper end is provided with a notch 15 forming an offset keeper 16. The keeper 16 is located at one end of the fastener 14, and at its 95 other end, each fastener 14 is supplied with an offset projection 17.

The numeral 18 denotes a rider preferably made of metal and of U-shape in longitudinal section, the rider 18 including an inner wall 19 and an outer wall 20. The walls 19 and 20 are connected by an integrally formed upstanding U-shaped yoke 21. In the yoke 21 is disposed a reinforcing filler 22 held in place by a rivet 23 passing through the yoke 21. The walls 19 and 20 of the rider are convexed in opposite directions to form guides 24 and 25 which diverge toward their upper ends, as clearly indicated in Fig. 4. The guides 25 which constitute a part of 110

the outer wall 20 are outwardly flexed at their lower ends, as shown at 26, for purposes to be set forth hereinafter. Mounted in the yoke 21 is an upstanding eye 27 to 5 which is attached a tab 28.

In practical operation, when the rider 18 is drawn upwardly by means of the tab 28, the rider slides over the fasteners 11 and 14, the same being received between the guides 10 24 and 25 of the rider. Because the guides at the respective sides of the rider converge, as they extend downwardly, as clearly shown in Fig. 4, the tongue 12 will engage beneath the keeper 16 when the rider is drawn upwardly, and the projection 17 will engage beneath the tongue, as clearly indicated in Fig. 4, to maintain the tongue engaged with the keeper.

When it is desired to open the shoe, the 20 finger pieces 10 are pulled in opposite directions, whereupon the rider 18 will slide downwardly over the fasteners 11 and 14, the parts coacting as guides.

In Fig. 6 of the drawings, a modified 25 form of the invention has been shown. Parts hereinbefore described have been designated by the numerals previously used, with the suffix "a". In this form of the invention, one side of the upper is shown 30 at 29 and has eyelets 30. The corresponding strip 6^a is provided with eyelets 31, and through the eyelets 30 and 31 is passed a lacing cord 32. This construction, preferably, is used at one side only of the shoe and 35 renders unnecessary such a part as the front piece 4. When the front piece 4 is used, the strips 6 and attendant parts are assembled with the part 4 and with the side 2 of the upper, and an adjustment is effected 40 by bringing the front piece 4 over onto the side 3 and stitching the same in place, or securing it otherwise, the stitching 5 being used in the present embodiment of the invention.

45 In Fig. 7 of the drawings, the numeral 52 denotes a flexible element as the part 4 or the part 2 of Fig. 3, the fasteners 53 being clamped directly onto the member 52, and the folded strips 6 of Fig. 3 being omitted.

50 In Fig. 8, parts hereinbefore described are denoted by numerals previously used, with the suffix "a". Fig. 8 may be compared with Fig. 3, and it will be noted that in the modification contemplated in Fig. 8, the side 3^a 55 is connected with the front piece 4^a by means of fasteners 51, like the elements 7 of Fig. 3, the strips 6^a being stitched, as shown at 50, to the sides 4^a and 2^a.

55 In Figs. 9 and 10 of the drawings, a modification in the invention is shown. In the 60 said figures, the numeral 70 denotes a corset, the edges of which are indicated at 71 and

72. Fasteners 84 of the kind hereinbefore described, are carried by the edges 71 and 72 of the corset, and the rider appears at 73. 65

A plate 74 is attached to the edge 71 at the lower end thereof and carries studs 75 and 76 spaced apart transversely of the corset. The plate 74 has a projection 77 on its lower edge, near to the stud 75. A plate 78 is attached to the edge 72 of the corset, near to the lower end thereof. The numeral 79 denotes a latch pivoted at 80 to the plate 78. The latch 79 has an offset arm 81, overlapping the plate 74. The arm 81 has a notch 82 in its upper edge, receiving the projection 76, and the arm has a notch 83 in its lower edge, near its free end, receiving the projection 75. The construction above described constitutes a means for connecting 80 the lower ends of the edges 71 and 72 of the corset, thus rendering the structure hereinbefore described of use on an article the longitudinal edges of which are completely separated, at times, a condition which does 85 not arise when the structure is applied to a shoe.

In practical operation, the stud 76 is received in a notch 82 and the stud 75 is received in the notch 83, thus preventing a 90 separation of the edges of the corset at the lower ends thereof. When it is desired to disengage the latch 79, a downward movement of the plate 78 will cause the latch 79 to swing downwardly, with the stud 75 as a fulcrum, the notch 82 being disengaged from the stud 76. The lower edge of the latch 79 then comes into contact with the projection 77, which, acting as a fulcrum, 95 disengages the notch 83 from the stud 76. 100

Having thus described the invention, what is claimed is:—

A device of the class described comprising parts having separable edges; fasteners carried by said edges, the fasteners on one edge being provided with tongues, the fasteners on the other edge being provided at one end with offset keepers receiving the tongues when said edges are brought together, the last specified fasteners being provided at 105 their other ends with projections which engage the tongues when the tongues are engaged with the keepers; and a rider slidable on the fasteners, and constituting means for bringing the fasteners together to cause the 110 tongues to interlock with the keepers. 115

In testimony that I claim the foregoing as my own, I have hereto affixed my signature in the presence of two witnesses.

WILLIAM M. McCLEAREN.
